(57) **CLAIM**

We claim the ornamental design for a battery charger, as shown and described.

DESCRIPTION

FIG. 1 is a top, right, front perspective view of a battery charger;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a top, right, front perspective view of a battery charger;

FIG. 9 is a right side view thereof;

FIG. 10 is a left side view thereof;

FIG. 11 is a front view thereof;

FIG. 12 is a rear view thereof;

FIG. 13 is a top view thereof; and,

FIG. 14 is a bottom view thereof.

Structural elements depicted by broken lines have been shown for the purpose of illustrating portions of the battery charger that form no part of the claimed design.

1 Claim, 6 Drawing Sheets
